UNITED STATES PATENT OFFICE

DANIEL V. BOWEN, OF ATTLEBORO, MASSACHUSETTS, ASSIGNOR, BY MESNE ASSIGNMENTS, TO L. E. WATERMAN COMPANY, OF NEW YORK, N. Y., A CORPORATION OF NEW YORK

DESIGN FOR A DESK STAND

Application filed April 8, 1931. Serial No. 39,399. Term of patent 14 years.

To all whom it may concern:

Be it known that I, DANIEL V. BOWEN, a citizen of the United States, residing in Attleboro, county of Bristol, and State of Massachusetts, have invented a new, original, and ornamental Design for a Desk Stand, of which the following is a specification, reference being had to the accompanying drawings, forming a part thereof.

Fig. 1 is a side elevational view of a desk stand showing my new design with the pen holding element in full lines and the base of the stand in broken lines; and Fig. 2 is a sectional view on line 2—2 of Fig. 1.

I claim:

The ornamental design for a desk stand, substantially as shown.

DANIEL V. BOWEN.
